Louis A. Bisson. ^{INVENTOR}

UNITED STATES PATENT OFFICE.

LOUIS A. BISSON, OF PHILADELPHIA, PENNSYLVANIA, ASSIGNOR, BY MESNE ASSIGNMENTS, TO GENERAL FIRE EXTINGUISHER COMPANY, OF PROVIDENCE, RHODE ISLAND, A CORPORATION OF DELAWARE.

FUSIBLE LINK AND STRUT.

Application filed August 3, 1920. Serial No. 400,924.

My invention relates to fusible links or struts of the type used in connection with thermally affected devices such as, for example, sprinkler heads in fire extinguishing systems and apparatus, safety devices on fire doors, actuating devices for fire alarms, refrigerating apparatus and similar means.

Among the objects of my invention is to provide a new and useful fusible link or strut in which the thermally affected element, preferably a fusible substance, will be normally under compression when in static and unfused condition.

Another object of my invention is to provide a new and useful means of the character aforesaid which will be free from the shearing and tearing stresses present in the prior devices thus wholly avoiding the "cold-flow" action that is incidental to the subjection of the fusible substance to such stresses, and, hence prevent premature operation of the controlled means.

A further object of my invention is to so construct the links and struts made in accordance with my invention that the elements thereof will be mutually thrown apart or asunder without danger of the same clogging or rendering the controlled means inoperative or merely partly operative.

A still further object is to provide the link or strut, so constructed, with heat insulating means whereby the link and strut will be of utility on sprinkler systems employing steam, hot water or other mediums normally at a temperature which if imposed upon the thermally active element, such as the fusible substance, would cause its operation.

A still further object is to construct the link or strut whereby the presence of the active element, such as the fusible substance, will be visible and also so exposing the same that it can be readily and easily tested.

A still further object is to provide the link or strut with means whereby an assured operation may be effected at the desired instant.

Other objects are to so construct and proportion the parts that great strength may be obtained in a relatively small and light weight means, that the required elasticity may be secured to give the structure an instantaneous and "snappy" action when set

into operation; and to arrange the parts relative to each other whereby the restraining capacity thereof will be at a maximum, the forces, normally stressing the same, being directed along lines of greatest effort for a rapid operation, but not with any tendency to produce any premature operation.

Other objects and advantages of my invention will more fully appear hereinafter.

Referring to the accompanying drawing where the same or similar reference characters are used to designate corresponding parts in the various views,

Fig. 1 is a view in elevation of a sprinkler head, embodying one form of device constructed in accordance with the invention;

Fig. 2 is a view in transverse section of one form of strain member constructed in accordance with the invention;

Figs. 3, 4 and 5 are similar views of other forms of strain members;

Fig. 6 is a view in elevation of a strain member showing additional fusible material in the gap between the elements of the strain member;

Fig. 7 is a view in elevation of a link embodying the invention;

Figs. 8, 9 and 10 are views in elevation illustrating lever types of struts embodying the invention;

Fig. 11 is a view in elevation illustrating a toggle type of strut embodying the invention;

Fig. 12 is a view in elevation illustrating a thrust type of strut embodying the invention;

Figs. 13 and 14 are views partly in section and elevation illustrating means for heat insulating the strain member utilized in any of the foregoing structures.

Referring more particularly to the drawing upon which are illustrated several representative modes of utilizing my invention, I have shown, as in Fig. 1, a sprinkler head comprising a nipple 1 provided with suitable means, as screw threads, for securement thereof to a conduit of a fire extinguishing system or the like. The nipple is provided with yoke arms 2 extending upwardly to a spray head 3 of any suitable type located opposite and in spaced relation to an outlet nozzle 4, the latter being normally closed by a closure cap 5. The spray

head 3 may be provided with a threaded stem 6 adapted to be adjustably rotated in a nut 7 preferably formed integral with the yoke arms 2. Any means, such as a pin 8, 5 may be utilized to permanently maintain the stem 6 in adjusted position. Both the stem 6 and the cap 5 may be provided with pivotal projections 9 and 10 respectively axially aligned and coincident with the axis 10 of the nipple 1 and spray head 3.

Between said projections 9 and 10 may be located a strain member or fusible strut comprising aligned retaining or socket elements 11 and 12 appropriately recessed at 15 an end of each to suitably and conveniently receive the pivotal projections 9 and 10 respectively. If, however, it be desired to form the ends of the strain member parts 11 and 12 with projections in lieu of recesses, 20 the projections 9 and 10, in that event should become recesses to receive the projections of said strain member. The other end of each of said socket elements is cut or tapered at an acute angle to provide surfaces 13 and 14 respectively, on the elements 11 and 12, and the elements are so located with relation to each other that those faces will normally lie substantially parallel to each other and in spaced relation, or out of contact with each 25 other, thereby providing an oblique gap 15 therebetween.

The tapered ends of said retaining or socket elements are further provided with recesses 16 and 17 adapted to receive the 30 ends of a bar, rod, strip or block of thermally sensitive or fusible material 18 having the property of fusing, melting, crumbling or otherwise disintegrating at a definite and predetermined temperature, but remaining 35 normally rigid under other degrees of temperature or conditions. The member or material 18 is of such length as to seat at its ends against the bottoms 19 and 20 of the recesses 16 and 17 and to extend through and be 40 visible in the gap 15. It will be further observed that member 18 is of a size to fill the recesses 16 and 17 so that the walls of the latter act as supports therefor against any possible lateral tendency to movement of 45 the material of the member 18. It is further noted that the gap 15 is made relatively narrow or thin so that while the surfaces 13 and 14 are normally out of contact, the space 50 through which the member 18 extends, in said gap, without lateral support, is so small that strain or "cold-flow" action of the material of the member 18 cannot occur and consequently the member 18 will not become 55 shortened under a continued application of pressure or force.

The surfaces 13 and 14 are inclined or formed oblique in order that when the member 18 ceases, by reason of fusing or melting, 60 to maintain the retaining or socket elements 11 and 12 in normally spaced relation, the

member 12 may be caused to move, due to the pressure of the fluid in the nozzle 4 acting against the cap 5, toward the element 11 whereupon the inclined face 14 contacts with the face 13 and slides thereover whereby 70 the elements are laterally cast from the sprinkler head. This act is substantially instantaneous and is completed before the extinguishing fluid issues from the nozzle 4.

While I have shown a strain member in 75 Fig. 1 in position for receiving the full thrust or pressure of the extinguishing fluid it is noted that the invention comprehends the utility of means constructed in accordance with the invention for operating under 80 forces that are merely component forces of or derived from the pressure of the extinguishing fluid in the sprinkler system. Examples thereof are shown in Figs. 8, 9, 10, 85 and 11.

Referring to Fig. 8, a lever type of strut is shown comprising an L-shaped lever member 21 provided with a recess 22 adapted to receive the projection 10 on the cap 5, and arms 23 and 24, the former extending upwardly and the latter laterally. The upper end of the arm 23 is provided with a fulcrum point or ridge 25 upon which is fulcrumed a lever 26, intermediate its ends, with one end thereof provided with a recess 27 adapted to receive the projection 9 on the stem 6, the other end of the lever 26 extending toward the free end 28 of the arm 24. The end 28 is appropriately shaped, as in the form of a hook, to present an end 29 opposite the end 30 of the lever 26. Between these ends, 29 and 30, may be interposed one of the strain members forming part of my invention, the recesses at the ends thereof respectively receiving the ends 30 and 29. It will 100 be observed that the lever 26 is of such a length that when the strain element is properly assembled in place relative thereto and the member 28, the lever 26 and the strain member form an obtuse angle slightly less than 180° with the lever 26 normally urging to increase said angle to 180°. Whenever the temperature of the surrounding atmosphere, and consequently the fusible member, reaches that at which the latter fuses or melts, 115 the strain member will immediately collapse due to the toggling effect of the lever 26 moving the socket element 11 toward the socket element 12, whereupon the inclined faces thereof contact and slide over each other, and the lever consequently released. The parts are cast aside and the sprinkler head permitted to open as above disclosed in connection with Fig. 1. It will be noted here that the strain member is normally placed under a very small component force of that acting at the nozzle and consequently the tendency for "cold-flow" of the fusible material 18 is accordingly reduced. The lever 26, as well as the arm 24, has a certain 125 130

amount of resiliency so that as soon as the strain member starts to collapse the rendering asunder of the link or strut structure will be very sudden or with "snap".

5 The strut structure shown in Fig. 10 is similar to that shown in Fig. 8 and comprises a strut or lever member 21' provided with a recess 22' adapted to receive projection 10 and an arm 23', a laterally extending 10 hook portion 28' being integrally provided near the lower end of the member 21'. A lever 26' is fulcrumed upon the upper end of the arm 23' and is provided with a recess 27' adapted to receive the projection 9 on 15 the stem 6, the other end 30' being in engagement in an end recess of the strain member interposed therebetween and the end 29' of the projection 28'. As in the structure shown in Fig. 8, the lever 26' and the strain 20 member are at an obtuse angle less than 180° and as soon as the fusible material 18 fuses or melts the lever 26', being normally under urging force to move away from the arm 23', causes the strain member to collapse and 25 force itself therefrom whereby the strut structure is cast asunder.

The strut structures illustrated in Figs. 9 and 11 are more in the nature of toggle struts, the former partaking, to a certain 30 extent, characteristics of the forms of devices shown in Figs. 8 and 10 and the latter being more of the nature of a simple toggle. The strut shown in Fig. 9 comprises a pair 35 of mutually engageable levers 21^a and 26^a, the former being somewhat longer than the latter, and provided at its free end with a preferably integral hook portion 28^a. Each member 21^a and 26^a may be provided with toggle legs or sections 31 and 32 respectively, 40 the latter having an end 33 fulcrumed in a recessed end 34 of the former, the lower end 35 of the member 31 and the upper end 36 of the member 32 respectively adapted to be fulcrumed in recesses 9' and 10' suitably 45 provided in the stem 6 and cap 5, such recesses 9' and 10' being provided in lieu of the projections 9 and 10, as in the form of device shown in Fig. 1. The free end of the lever 26^a may be provided with an end 30^a slightly up-turned, as shown, in spaced relation and opposite to an end 29^a, where the same are received in the end recesses, of the strain members. The latter is so interposed therebetween as to form with the up-turned portion of the lever 26^a an obtuse angle slightly less than 180°, as in the forms 55 shown in Figs. 8 and 10, hereinbefore described. As soon as the fusible material 18, fuses, melts or crumbles, the lever 26^a, being 60 normally under urging force to move away from the arm of lever 21^a, causes the strain member to collapse and free itself therefrom whereby the strut structure is cast asunder, as in the forms above described and shown 65 in Figs. 8 and 10.

The toggle structure shown in Fig. 11 comprises lever legs or sections 31' and 32' mutually in fulcrumed disposition with the upper end 33' of the former fulcrumed in the recessed end 34' provided in the lower portion of the latter. The upper and lower ends 36' and 38' respectively of the members 32' and 31' may cooperate with the recesses 9' and 10' of the members 6 and 5 respectively as in the case of the ends 36 and 35 of the device shown in Fig. 9. Each of the lever members 31' and 32' is provided with a laterally extending arm 21^b and 26^b disposed in substantially parallel and spaced relation to receive and normally maintain 70 therebetween the strain member forming a part of the herein disclosed invention. This strain member may extend throughout the length of the space provided between the members 21^b and 26^b with the socket elements 11 and 12 thereof abutting the same, but if desired, and preferably so, blocks 37 and 38 of any suitable rigid material, preferably heat insulating substance, may be interposed between the respective socket members 11 and 12 and the arms 21^b and 26^b 75 which tend to approach each other. The pressure between the contacting parts, particularly the elements, 11, 12, 37, 38, 21^b and 26^b, will be normally sufficient to maintain 80 the same in position until the proper conditions exist to cause a correct operation of the device, but it may be noted that if it be desired, the members 21^b, 26^b, 11 and 12 85 may be provided with recesses 39, 40, 17' and 16' respectively adapted to receive counterpart projections 39', 40', 29^b and 30^b formed on the ends of the blocks 37 and 38. In this fashion the strain member and 90 the blocks 37 and 38 will be assured against lateral movement and consequent disengagement from each other or from the members 21^b or 26^b, as from vibrations or other causes, whereby premature operation may be 95 avoided. When the fusible material 18, however, melts or otherwise yields the parts 100 11 and 12 will approach and slide over each other, to be cast aside and consequently the arms 21^b and 26^b will also rapidly approach each other to a point where the toggle 105 structure will be cast asunder, similarly to the action of the other forms of device described in the foregoing.

In Fig. 7 is shown a tension strut or link embodying the invention. It comprises a pair of side members 41 and 42 each provided at an end thereof with laterally extending thrust pieces 43 and 44 respectively and at the other ends thereof with suitably apertured bent portions 45 and 46 by which the parts 41 and 42 may be attached to tensioning elements adapted to pass through the apertures 47 and 48 thereof. The members 41 and 42 are so assembled as 110 to present the abutment pieces or portions in 115 120 125 130

opposed spaced relation and a strain member 5 may be interposed therebetween with the opposite ends of such strain member abutting said thrust members 43 and 44. The 10 portions 45 and 46 are laterally bent or offset from the body portions of the members 41 and 42 in order to locate them in alignment and coincident with the axis or the longitudinal medial plane of the strain member 15 whereby the line of force or tension acting through the link organization will be along a central line or plane. If the line of force tending to render the link structure asunder were at an angle to said line or plane, there would be a greater tendency for the members 41 and 42 to rock the strain member whereby the members 41 and 42 might separate and operate prematurely. Where the line of thrust is parallel to said 20 members 41 and 42 and along the axis or longitudinal medial plane of the strain member, such action can not occur. In use, the thrust pieces 43 and 44 normally tend to approach each other, and therefore, when 25 the material 18 yields, as by melting or crumbling, the socket members 11 and 12 will approach and slide over each other so as to cause the members 41 and 42 to move laterally away from each other. This movement will be ample for the elements 43 and 44 to clear each other as they move toward each other.

In Fig. 12 is shown a strut or thrust link comprising a pair of thrust plates 49 and 50 30 adapted to slide longitudinally along each other. They may be placed in contact with each other, as shown, and at a slight angle to the line of thrust or force acting on the cap 5, whereby the upper and lower ends 51 and 52, respectively, of the plates 49 and 50, 35 may be received in suitable recesses, as recesses 9' and 10' formed in the stem 6 and cap 5 respectively. Near the ends 51 and 52 may be formed on the plates 49 and 50 40 laterally disposed retaining sockets 53 and 54, corresponding to the retaining or socket member 11 of Fig. 1, and the other ends of the plates 51 and 52, respectively 45 are formed with terminal retaining sockets 55 and 56, corresponding to the retaining or socket member 12 of Fig. 1. These 50 sockets, in pairs, namely 53 aligned with 56 and 54 aligned with 55, form strain members for the strut or thrust link structure, 55 there being two strain members instead of one. Two strain members, however, are not essential inasmuch as one would suffice. The aligned socket members 53 and 56 or 54 and 55 are, as in the forms shown in 60 Figs. 1 and 2, appropriately recessed to conveniently receive a bar, rod, strip or block of thermally sensitive or fusible material 18 having the property of fusing, melting, crumbling or otherwise disintegrating at 65 a definite and predetermined temperature

but remaining normally rigid under other degrees of temperature and conditions. Each of the sockets 53, 54, 55 and 56 is cut or tapered at an acute angle to provide surfaces which normally will lie substantially parallel to each other with the faces of the sockets 53 and 56 or 55 and 54 in slight spaced relation to provide therebetween an oblique gap, as the gap 15 in the form shown in Figs. 1 and 2. Normally, 70 the plates 49 and 50 are under a strain and tend to move or slide along each other but are restrained from such movement by reason of the bars or blocks of material 18 maintaining said plates in position with the 75 tapered ends of the sockets thereof in spaced relation. As soon, however, as the material 18 yields, the plates 49 and 50 immediately slide relatively to each other until the inclined surfaces of the adjacently 80 located and aligned sockets come into contact. Further movement will cause the sockets or socket portions on said plates to slide over each other and to cause the plates 49 and 50 to laterally separate and be cast 85 asunder, as in the case of the parts 11 and 12 flying apart in Fig. 1.

Any of the strain members herein described or referred to may, if desired, be provided with means for more effectively 90 causing the operation of the device, particularly when a relatively hard and slow acting thermally sensible or fusible material is being used. Such means is illustrated in Fig. 3, wherein the retaining or 95 socket members 11 and 12 may be provided with cutting edges 57 and 58 so that as the faces 13 and 14 slide over each other the cutting edges 57 and 58 will readily cut the material 18 thereby aiding and hastening the action of strain member. For the purpose of forming said cutting edges without the same forming or occupying 100 any groove or recess in the bar or block of material 18 and without removing a substantially large amount of material from the inner walls of the sockets, small back 105 cuts or recesses 59 and 60 may be made in the walls of the socket members 11 and 12, adjacent the faces 13 and 14, so as to provide the sharp edges 57 and 58. It will be noted also that these cutting edges are located so as to cut the material on opposite sides and substantially along the same surface or plane, the surfaces 13 and 14 being, at the 110 time of action of the cutting edges, in contact with each other, and consequently in the same plane.

The strain member or element may be of 115 any desired form and cross-section, and as an illustration of a desirable form, I have shown in Fig. 4 one of double conoidal shape, both the socket members 11' and 12' and the thermally sensitive material 18' being 120 tapered at the ends, the points or ends 125

61 and 62 of the socket members 11' and 12' being adapted to be received in the recesses 9' and 10' of the stem 6 and cap 5. This form of strain member is strongest 5 when following the lines of a parabola so that the element 18', regarded as a solid formed by the revolution of a pair of parabolas abutting at their bases, will be of maximum strength with a minimum amount of 10 material. Inasmuch as the same is symmetrical about the axis which is also coincident with the line of force acting thereon, the thrust upon the tapered surfaces thereof has the same effect as if the ends of 15 the member 18' were flat and were seated against flat surfaces at a normal to the line of force acting therethrough. The socket members, also may be made thin, light and devoid of corners or projections whereby 20 the projection of the same by the sprinkler head parts may be facilitated and effected with a minimum chance for interference as the elements or parts of the strut or link structure are cast asunder. It may also be 25 observed that the corners 57' and 58' may also serve as shearing or cutting edges when the member 18' is in a state of fusing and as the inclined surfaces of the members 11' and 12' slide over each other.

30 In some cases it may be desirable to make the retaining elements of the strain member of thin metal. In that event the inclined surfaces, 13 and 14 would not have sufficient area of contact to insure efficient operation 35 of the parts. I have shown in Fig. 5, in part, a strain member with the retaining elements or sockets made of thin metal. Each socket member 11 and 12 may be provided with laterally extending fins 63 and 40 64 on the adjacent inclined ends thereof, with faces or surfaces 18' and 14' of sufficient area to give proper sliding contact therebetween. These fins may be of any 45 shape or form desired to accomplish the end sought, those shown in Fig. 5 being in the form of flanges preferably spun into the form shown for the socket members 11 and 12.

50 Where sprinkler heads are to be used in a system using hot water or steam as an extinguishing medium or agent it is obvious that the heat would ordinarily be conducted by the metal of the sprinkler head to the fusible link or strut, which is also of metal, and would cause the operation of the same at 55 an undesirable time. In order that the device constructed in accordance with my invention may be of use in sprinkler heads in systems using hot water or steam, which is at a temperature higher than that at which the material 18 or 18' fuses, I may provide heat insulating means therefor. In Figs. 13 and 14 I have shown two modes of insulating the strain member from the other parts 60 of the link or strut structure. In Fig. 13 the ends of the strain member may be provided with caps 65 made of any suitable heat insulating material, such as hard rubber, bakelite, paper fibre, or similar materials. The cap may be provided with two recesses 70 66 and 67, the former to receive an end of the strain member and the other to receive heat insulating materials 68, such as asbestos or compositions comprising asbestos as an essential ingredient and similar materials. 75 Within the recess 67 may project and press against the material 68 the ends 9 or 10 of the stem 6 and cap 5, or the ends 29 and 30 of the hook 28 and the lever 26, or the ends 29' and 30' of the hook 28' and lever 26', or 80 the ends 29^a and 30^a of the hook 28^a and the lever 26^a, or the projections 29^b and 30^b of the blocks 37 and 38, or the ends 61 and 62 of the strain member shown in Fig. 4.

85 Fig. 14 is somewhat similar to Fig. 13, except that the ends of the strain member are recessed to receive hollow bodies 69, such as glass spheres, having a vacuum therein. These evacuated bodies will act as efficient insulators of heat. Inasmuch as glass itself 90 is a poor conductor of heat, it will be apparent that the heat that the glass may itself conduct will be inappreciable. The other parts of the strut or link structure with which the strain member is to be associated 95 or combined, may also be recessed to receive the other half of said bodies as is clearly shown in Fig. 14.

100 It will be further observed that the gap 15 between the faces 13 and 14 need not be open but may, if desired, be filled with solder or fusible material, such structure being shown in Fig. 6 in which the gap 15 is shown filled with fusible material 70. The operation of the device, however, will not be affected or changed by the presence of such material in the gap 15.

105 It is preferable, however, to omit such material in said gap. One of the reasons for this is that an inspection of the strain element may be made by looking through the gap to perceive the presence of the bar, piece or block of fusible material 18 in place. With the material 70 in place in the gap 15 110 there is no assurance that the bar or block 18 is in place since it is possible to omit it and merely fill the material 70 in said gap, which, of course, would permit cold-flow action and consequently the operation of the strain member prematurely. By having the gap 15 always open it is possible to visually 115 ascertain the presence of the element 18.

120 The gap 15 also offers a space for the introduction of a test element, such as a needle, which may be moved through the gap 15 with the point of the needle against the element 18. If the element 18 is of the proper material, such as fusible solder, a characteristic mark will be made, in the surface 125 thereof exposed between the surfaces 13 and 130

14, by the point of the needle. The invention is therefore both adapted to visibility and test of the yieldable element.

While I have herein described and illustrated upon the drawing some embodiments of my invention it is to be understood that the invention is not limited to the particular details and arrangement of parts shown and described, but that the invention comprehends other forms, details and arrangements of parts as do not depart from the spirit of the herein-disclosed invention and the scope of the appended claims.

Having thus described my invention what I claim and desire to secure by United States Letters Patent is:—

1. In a sprinkler head, the combination of normally spaced members and thermally yieldable means for normally maintaining said members in spaced relation, said members being movable toward each other upon the yielding of said means, and means for normally maintaining said yieldable means substantially free from strain.

2. In a sprinkler head, the combination of normally spaced members, said members being provided with opposed inclined surfaces, thermally yieldable means between said members normally maintaining said members in spaced relation, said members being movable toward and slidable over each other upon the yielding of said means, and means for normally supporting said yieldable means against cold flow.

3. A strut for fire extinguishers comprising a thermally yieldable member and means for normally placing said member under compression, said means being adapted upon the yielding of said member to be cast asunder and being adapted also for normally sustaining said yieldable member from strain.

4. A strut for fire extinguishers, comprising a thermally yieldable member, and means for normally placing said yieldable member under compression, said means comprising spaced members adapted upon the yielding of said yieldable member to engage each other for the casting asunder thereof, and means for supporting said yieldable member against cold flow when normally placed under compression.

5. A strut for fire extinguishers, comprising a thermally yieldable member, and means for normally placing said yieldable member under compression, said means comprising spaced members having opposed inclined surfaces adapted to engage with and slide over each other upon the yielding of said yieldable member for the casting asunder of said members, and means for laterally supporting said yieldable member against cold flow when normally placed under compression.

6. A strut for fire extinguishers, com-

prising a thermally yieldable member and recessed members on said yieldable member, the ends of said yieldable member being seated in the recesses of said recessed members, said recessed members being normally maintained in spaced relation by said yieldable member and adapted upon the yielding of said yieldable member to engage each other for the casting asunder thereof.

7. A strain element for thermally controlled devices, comprising aligned recessed retaining members and thermally yieldable means seated in the recesses of said retaining members whereby the latter are normally maintained in spaced relation and adapted to engage each other upon the yielding of said yieldable means.

8. A strain element for thermally controlled devices, comprising aligned recessed retaining members and thermally yieldable means placed under compression between said retaining members, said yieldable means being seated in the recesses of said retaining members whereby the latter are normally maintained in spaced relation, said retaining members being provided with opposed inclined surfaces adapted upon the yielding of said yieldable means to mutually contact and cause said retaining members to slide over each other along said inclined surfaces.

9. A strain element for thermally controlled devices, comprising aligned recessed retaining members, thermally yieldable means extending in the recesses of said retaining member and placed under compression therebetween, said yieldable means normally maintaining said retaining members in spaced relation, said retaining members being provided with opposed inclined surfaces adapted upon the yielding of said yieldable means to mutually contact and cause said retaining members to slide over each other along said inclined surfaces and means on said retaining members for laterally supporting said yieldable means.

10. A strain element for thermally controlled devices, comprising aligned recessed retaining members, thermally yieldable means extending in the recesses of said retaining member and placed under compression therebetween, said yieldable means normally maintaining said retaining members in spaced relation, said retaining members being provided with opposed inclined surfaces adapted upon the yielding of said yieldable means to mutually contact and cause said retaining members to slide over each other along said inclined surfaces and means on said retaining members for shearing said yieldable means during the relative movement of said retaining members.

11. A strain element for thermally controlled devices, comprising aligned recessed retaining members, thermally yieldable

- means extending in the recesses of said retaining member and placed under compression therebetween, said yieldable means normally maintaining said retaining members 5 in spaced relation, said retaining members being provided with opposed inclined surfaces adapted upon the yielding of said yieldable means to mutually contact and cause said retaining members to slide over 10 each other along said inclined surfaces and cutting edges adjacent said inclined surfaces for cutting said yieldable means during the relative movement of said retaining members.
12. A strain element for thermally controlled devices, comprising spaced retaining members, thermally yieldable means placed under compression between said retaining members for normally maintaining the same 20 in spaced relation, said retaining members being provided with inclined surfaces located in spaced parallel relation, and means for affording a lateral support for said thermally yieldable means when placed under compression, said retaining members adapted upon the yielding of said yieldable means to mutually contact and relatively slide along said inclined surfaces for a casting asunder thereof.
13. A strain element for thermally controlled devices, comprising spaced compression members, thermally yieldable means placed under compression between said compression members, and operative to normally 30 maintain said compression members in spaced relation, means on said compression members operative upon the yielding of said yieldable means to cast said members asunder as said members move toward each other and heat insulating means on said compression members.
14. In a sprinkler head, the combination of a strut, a lever fulcrumed on said strut, a strain element having thermally yieldable means placed under compression and being interposed between said strut and said lever substantially without receiving direct stress therefrom transversely of the line of compression and normally restraining the separation of said strut and lever.
15. In a sprinkler head, the combination of mutually fulcrumed levers, a strain member having a thermally yieldable means placed under compression between said levers, substantially without receiving direct stress therefrom transversely of the line of compression whereby upon yielding of said strain member said levers are cast asunder.
16. In a sprinkler head, the combination of mutually fulcrumed levers, a strain member having a thermally yieldable means placed under compression by said levers, substantially without receiving direct stress therefrom transversely of the line of compression, said member normally maintain- 50
- ing said levers in inoperative position, one of said levers and said strain member forming an angle less than a straight angle, said strain member and said last mentioned lever being urged to form a straight angle upon the yielding of said strain member.
17. In a sprinkler, the combination of a strut, a lever fulcrumed on said strut, fusible material placed under compression interposed between said strut and said lever and normally restraining the separation of said strut and lever.
18. In a sprinkler head, the combination of a pair of spaced members, said members being provided with inclined surfaces adjacently located in spaced parallel relation, fusible material interposed between said members and normally maintaining said members and said surfaces in spaced relation, said member having means for laterally supporting said fusible material when normally placed under a stress, and means for placing said fusible material under strain whereby, when the fusible material yields upon a rise in temperature, said members move toward and slide over each other for a casting asunder thereof.
19. A link or strut for thermally controlled devices, comprising relatively movable members and thermally yieldable strain material placed under compression by said members, substantially without receiving direct stress therefrom transversely of the line of compression, said strain means normally maintaining said members inoperative, said members being operative to mutually separate upon the yielding of said strain means.
20. A link or strut for thermally controlled devices, comprising relatively movable members and thermally yieldable strain material normally placed under compression by said members, substantially without receiving direct stress therefrom transversely of the line of compression, said strain means being provided with opposed inclined surfaces normally out of contact with each other, said members operative upon yielding of said strain means to mutually separate by the sliding contact of said inclined surfaces.
21. A strain element for thermally controlled devices, comprising relatively movable members, fusible material placed under compression by said members, said fusible material normally maintaining said members in spaced relation, means on said members operative upon the fusing of said fusible material to cause a mutual separation of said members, and heat insulating means on said members adapted to insulate said members and said fusible material from the conduction of heat thereto.
22. In a sprinkler head, the combination of relatively movable members, a thermally

yieldable strain member comprising fusible material placed under compression by said movable members, said strain member normally maintaining said movable members in operative position, means on said strain member operative upon fusing of said fusible material to cause a yielding of said strain member and heat insulating material between said movable members and said strain member adapted to insulate said strain member and said fusible material from the conduction of heat thereto.

In witness whereof, I hereby set my hand this 31st day of July, 1920.

LOUIS A. BISSON.
